UNITED STATES PATENT OFFICE.

SAMUEL A. KIMMELSTIEL, OF NEW YORK, N. Y.

DESIGN FOR A BASE FOR DISPLAY STAND.

Application filed August 13, 1925. Serial No. 14,418. Term of patent 3½ years.

To all whom it may concern:

Be it known that I, SAMUEL A. KIMMELSTIEL, a citizen of the United States, residing at New York, in the county of New York and State of New York, have invented a new, original, and ornamental Design for Base for Display Stand, of which the following is a specification, reference being had to the accompanying drawing, forming a part thereof.

Fig. 1 is an elevational view of a base for a display stand, showing my new design.

Fig. 2 is a plan view on the line 2—2 of Fig. 1.

I claim:

The ornamental design for a base for display stand, as shown.

SAMUEL A. KIMMELSTIEL.
